DESIGN FOR A PEG FOR HOLDING VINES UPON THE SOIL

Joseph E. Johnston, Alamosa, Colo.

Application October 17, 1944, Serial No. 115,824

Term of patent 14 years

(Cl. D35—2)

To all whom it may concern:

Be it known that I, Joseph E. Johnston, a citizen of the United States, residing at Alamosa, in the county of Alamosa and State of Colorado, have invented a new, original, and ornamental Design for a Peg for Holding Vines Upon the Soil, of which the following is a specification, reference being had to the accompanying drawing, forming a part thereof.

In the drawing:

Figure 1 is a perspective view of a peg for holding vines upon the soil, showing my new design, and

Figure 2 is a side elevational view thereof.

I claim:

The ornamental design for a peg for holding vines upon the soil, as shown.
